CLAIM

The ornamental design for an end panel insulator for a temperature-controlled rotary cylinder, as shown and described.

DESCRIPTION

FIG. 1 is a perspective view of an end panel for a temperature-controlled rotary cylinder showing our new design;

FIG. 2 is a front elevational view thereof;

FIG. 3 is a rear elevational view thereof, it being understood that the pattern shown represents quilted insulating material;

FIG. 4 is a side elevational view thereof;

FIG. 5 is a side elevational view thereof, showing the side opposite to that illustrated in FIG. 4.
